DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

No Drawing. 9 Pages Specification

Silicone modified unsaturated polyesters are prepared by reacting polyesters, the glycol component of which is at least 50 mole percent neopentyl glycol, 2,2,4-trimethylpentane-1,3-diol or 1,4-cyclohexanediethanol with a silicone compound of the general formula

wherein at least one R is hydroxy or alkoxy from C₁ to C₁₀ and the remaining R's are hydrogen or other organic radicals having from 1-40 carbon atoms, and n is an integer sufficient to result in a molecular weight of from 500 to 1000.

The silicone modified polyesters are blended with polymerizable vinyl monomers to form gel coats having good physical properties.
